H. SCHWENNEKE,

COVER FOR BOXES.

APPLICATION FILED FEB. 8, 1921.

1,416,420.

Patented May 16, 1922.

Inventor:
Hans Schwenneke,
By G. W. S. Cimes, atty.

UNITED STATES PATENT OFFICE.

HANS SCHWENNEKE, OF CHICAGO, ILLINOIS, ASSIGNOR TO GLOBE PAPER BOX COMPANY, OF CHICAGO, ILLINOIS.

COVER FOR BOXES.

1,416,420.

Specification of Letters Patent. Patented May 16, 1922.

Application filed February 8, 1921. Serial No. 443,449.

To all whom it may concern:

Be it known that I, HANS SCHWENNEKE, a citizen of the United States, and a resident of Chicago, in the county of Cook and State 5 of Illinois, have invented certain new and useful Improvements in Covers for Boxes, of which the following is a specification.

My invention relates to pasteboard boxes, such as used for containing merchandise, for 10 example, and is particularly directed to the cover of the box where a folding means or support is secured to the inside face, adapted to be adjusted to serve as a support for the box when inclined obversely in the cover 15 element.

A device incorporating the present invention is shown in the accompanying drawing in which Fig. 1 shows a vertical section through the box and cover arranged to display the contents of the box.

Figure 2 shows a vertical section through the box with the cover in place normally, enclosing the contents.

Figure 3 is an elevation of the box as appearing from left of Fig. 1.

The box 1 and its cover 2 are of well known form. The cover is of such dimensions as to fit loosely, but securely over the box. The present invention contemplates 30 attaching (adhesively or otherwise) a folded pasteboard (or other suitable material) strip which has been suitably creased to form the sides, 3, 4, 5, and 6 of the support. The relative lengths of the sides 3, 4, 5 and 35 6 are such as to make the sum of the lengths 4 and 5 equal to the sum of the lengths of 3 and 6 and the relative lengths of 4 and 6 such as when side 5 has an angular relation with the bottom surface of the cover as that 40 desired for the inclination of the open box the side 6 will form an angle of ninety degrees with the side 5. However, this angular relation of sides 5 and 6 may be varied if desired, though greater stability and 45 security will obtain by having this relation ninety degrees as stated.

The sides 4 and 5 combined equaling the lengths 3 and 6, combined as stated, it is possible to fold the sides so the side 6 will 50 be flat upon the inside face of the top of the cover 2 and the facing sides 4 and 3 and 5 and 6 will be in engagement. This relation and disposition of the support is shown in Fig. 2 wherein the support does not mate-

rially encroach upon the containing space of 55 the box 1.

From the foregoing it is clear that where the contents of the box are to be displayed on a counter (or other surface) the cover is removed and placed obversely on the surface of the counter and the support member unfolded by pulling the sides 4 and 5 upward until the angular relation of side 5 is that desired for the bottom of the box when in the position shown in Fig. 1.

The end face or flange of the cover at the right retains the box from sliding, and it is thus held securely and the contents are exhibited saliently.

The drawings and descriptions thereof 70 contemplate but one form of box cover and support employing the present invention and it is to be understood that I do not wish to be limited to the exact structure shown, but desire to include and cover all modifications either amplifying the support member or curtailing it in view of the subjoined 75 claims.

I claim:

1. In a cover for boxes, a dually hinged 80 collapsible member thereof adapted to be adjusted to form a support for one end of the box.

2. In a cover for boxes, a dually hinged collapsible member thereof secured to its 85 inner face which is designed to be opened to form a support for the box.

3. In a cover for boxes, a dually hinged collapsible member thereof secured to its inner face which is designed to be opened to 90 form an inclined support for one end of the box.

4. In a cover for boxes, a dually hinged collapsible support member attached to its inner face.

5. In a cover for boxes, a dually hinged support member attached to its inner face.

6. In a box consisting of a containing element and a cover element, a dually hinged collapsible support member attached to the 100 cover whereby when the support member is opened it will form a support for one end of the containing element.

7. In a box consisting of a containing element and a cover element, a dually hinged 105 collapsible support member attached to the inside of the cover whereby when the support member is opened it will form a sup-

port for the one end of the containing element.

8. In a box consisting of a containing element and a cover element, a dually hinged 5 collapsible support member attached to the inside of the cover whereby when the cover is placed obversely and the support member is opened the support member will form a support for one end of the containing element.

9. In a pasteboard box, a flanged cover therefor, a dually hinged folding member attached to the inside face of the cover normally folded, adaptations for allowing the 15 unfolding of the folding member and for employing it as a support for one end of the box when the other end of the box is adjusted to rest obversely inside the cover, one 20 end of the box engaging an end flange of the cover.

10. In a box, a cover therefor, a dually hinged folding member having its sides continuous, attached to the inside face of the cover, adaptations for allowing the unfolding 25 of the folding member and for then employing it as a support for one end of the box when the other end of the box is adjusted to rest obversely inside the cover, one 30 end of the box being retained from sliding by the cover.

11. In a box, a cover therefor, a dually hinged folding member having its sides continuous, attached to the inside face of the cover, adaptations for allowing the unfolding 35 of the folding member and for then employing it as a support for one end of the box when the other end of the box is adjusted to rest obversely inside the cover.

12. In a box, a cover therefor, a dually 40 hinged folding member having its sides continuous, but of different length, two adjacent sides combined equalling the length of the

two adjacent other sides, said folding member being adapted to be attached to the inside face of the cover, so when the said folding member is unfolded and the box is inclined obversely to the inside of the cover the said folding member will form a support for the box along one of the sides of the said folding member.

13. In a box, a cover therefor, a dually hinged folding member having four sides of unequal length, two adjacent sides combined equalling the length of two adjacent other sides, said folding member being adapted to 45 be attached to the inside face of the cover, so when the said folding member is unfolded it forms an unsymmetrical polygon wherein one side is parallel with the inner face of the cover and a side not adjacent to the latter 50 side forms a resting face disposed in the same lateral direction as the inside face of the cover, but at an angle with the said inside face of the cover.

14. A collapsible support for boxes consisting of a dually hinged folding member having four sides of unequal length, two adjacent sides combined equalling the length of two adjacent other sides, said folding member being adapted to be attached to the 55 inside face of the cover of the said box, so when the said folding member is unfolded it forms an unsymmetrical polygon wherein one side is parallel with the inner face of the cover and a side not adjacent to the latter 60 side forms a resting face for the said box disposed in the same lateral direction as the inside face of the cover, but at an angle with the said inside of the cover.

In witness whereof, I hereunto subscribe 65 my name this 3rd day of February, A. D. 1921.

HANS SCHWENNEKE.
